(57) **CLAIM**

The ornamental design for a body of a body composition analyzer, as shown and described.

DESCRIPTION

FIG. 1 is a front, top, and right side perspective view of a body of a body composition analyzer according to the new design;

FIG. 2 is a rear, top, and left side perspective view of the body of the body composition analyzer of FIG. 1;

FIG. 3 is a front elevational view of the body of the body composition analyzer of FIG. 1;

FIG. 4 is a rear elevational view of the body of the body composition analyzer of FIG. 1;

FIG. 5 is a left side elevational view of the body of the body composition analyzer of FIG. 1;

FIG. 6 is a right side elevational view of the body of the body composition analyzer of FIG. 1;

FIG. 7 is a top plan view of the body of the body composition analyzer of FIG. 1; and,

FIG. 8 is a bottom plan view of the body of the body composition analyzer of FIG. 1.

The broken lines are included for the purpose of illustrating portions of the body of the body composition analyzer that form no part of the claimed design.
